UNITED STATES PATENT OFFICE.

THOMAS V. ALLIS, DECEASED, LATE OF PITTSBURGH, PENNSYLVANIA; BY MANNORA
E. ALLIS, ADMINISTRATRIX, OF PITTSBURGH, PENNSYLVANIA.

PUSHER FOR FURNACES.

Application filed May 18, 1921. Serial No. 470,877.

To all whom it may concern:

Be it known that, THOMAS V. ALLIS, late a citizen of the United States, deceased, late of Pittsburgh, in the county of Allegheny and State of Pennsylvania, invented certain new and useful Improvements in Pushers for Furnaces, of which the following is a specification.

The present invention relates to the art 10 of charging sheet and tinplate bars into furnaces, and is for use particularly in connection with a furnace hearth of certain construction and a method of heating sheet and tinplate bars, invented by Thomas V. 15 Allis, and covered by two patents issued to him as follows, to wit: pair heating furnace hearth, dated August 6th, 1912 Number 1,034,858, and reissued December 14, 1915, Reissue Number 14,032, and method of heating sheet-bars, dated December 10, 1912, Number 1,046,933. The present invention is 20 a continuation in part and modifications of a charging machine shown in Patent No. 25 1,402,036, dated January 3rd, 1922, entitled Method of, and machine for charging sheet and tinplate bars into furnaces, by the same inventor, Thomas V. Allis.

Reference is made to all the above 30 patents for a fuller understanding and description of the present invention in connection with the art in which it is used. In the last named patent, a fixed or stationary charging machine or pusher is described in connection with its use for charging bars placed 35 on a stationary charging table in front of the charging door of a furnace. The present type of pusher is a modification of said pusher in the earlier application, and it will 40 be noted that the machine described in the present application is preferably used without the intermediate charging table, the pusher being placed directly in front of the furnace hearth to be charged with tinplate 45 bars, and may be partially attached thereto.

The bars to be charged are charged in a collection, at every forward movement of the pusher head in the present invention, and it is observed that the "gang" method 50 of charging is a distinct advantage, as will be seen from the description in the last named patent.

In the accompanying drawings forming 55 part of this specification I have shown an example of the physical embodiment of the

invention which has proven in practice to be the best form devised by the present inventor for the purpose intended.

Figure 1, is a plan view of the invention.

Figure 2 is a side elevation of Figure 1. 60

Figure 3 is an end elevation taken from the left of Figure 2.

Figure 4 is an end view taken from the right of Figure 2.

Figure 5 is a diagrammatic plan view of 65 the pusher in operative position in front of the charging end of a bar furnace.

Figure 6 is a partial detail transverse cross section of the pusher head of my invention on line 6—6 of Figure 7. 70

Figure 7 is a longitudinal vertical section of the end portion of the pusher head on line 7—7 of Figure 6.

Figure 8 is a transverse sectional detail 75 showing the bar support table on line 8—8 of Figure 1.

The present type of pusher comprises the following parts. The numeral 1 indicates a preferably cast metal base plate which is secured to the floor or foundation preferably of concrete 2, and said plate carries rigidly mounted thereon a pair of "opposite hand" or reversed in position upright supports 3, 4, which have their web plate portions ribbed at 5, 5 etc. for stiffening purposes. Also rigidly mounted on the base plate 1, is a motor 6 of suitable power to drive the pusher head 7 which will be described hereinafter. The said motor 6 is coupled to a slow-down worm-gearing 8, the latter also mounted rigidly on the base plate 1. It is evident that as the speed of the motor is comparatively high, and the pusher head moves slowly, the speed of the motor must be reduced by means of the worm-gearing 8, before its power can be used properly. The shaft 9 of the worm-gearing 8 is mounted on its opposite ends in bearings 10, 10, which are in turn mounted 80 on the upright supports 3, 4 above described. On the ends of the shaft 9, are the driving sprockets 11, 11, which form the means of driving the chains 12, 13, the latter passing over "idler" sprockets 14, 15 respectively. 85

On the end of the pusher remote from the base plate 1, are a pair of standards, 16, 16 secured preferably to the floor 2, the lower extremities 17, of said standards be- 90

ing preferably made shorter than ordinarily would reach the floor 2, when the machine is in normal position. The purpose of having said standards 16, 16 made with their bases 17, 17 a short distance above the floor 2, when the pusher is in normal or operative position, is to permit thin "shim" plates 52, 52 of proper thickness to be placed under said standards, and enable the pusher head 10 teeth 18, 18 etc. to be placed at a suitable elevation with reference to the grooves of the furnace hearth 20, in order to adjust said teeth to slidably reciprocate in the hearth grooves. The standards 16 have 15 preferably a stiffening web 21, and a pair of outstanding flanges 22, 22, the latter being curved at 23 as shown in order to permit of a suitable connection being made by the pusher to the furnace 24. The furnace 20 hearth 20, has preferably an outwardly extending fore-plate lip 25 which is supportingly mounted on the support bracket 26, the latter being directly attached to the front of the furnace 24, as shown.

25 Mounted rigidly on the upright supports 3, and 4 are a pair of longitudinal ways 27, 27 having their upper faces 28, 28 "machined" smooth so that the pusher head 7 resting thereon can be readily propelled 30 along said ways, as will be understood. On the ends of the ways 27, 27, nearest the furnace 24 they are attached rigidly to the standards 16, 16. On the under or lower side of the ways 27, 27 is mounted in suitable bearings 29, 29, a shaft 30, on the ends of which are the sprockets 14, and 15 before described herein. It is noted that the ways 27, 27 are inclined in position, as the bars 35 tend to "stack" better when in this inclined position against the end teeth 18, 18 of the pusher head 7, gravity assisting in the operation, and it is found that the pusher head 7 operates more smoothly along the ways 27, 27 when under load pushing the bars 31, 32, etc. into the furnace 24. Between the ways 27, 27 is suspended the grooved bar support table 33, which is rigidly attached to said ways, and forms a means of rigidly connecting the two standards 16, 16 with each other and with the upright supports, 3 and 4, thus making the whole pusher a firm and unitary structure, capable of good mill service. Attention is called to the cut-away base portions 34, 34 of the grooves 35, of the bar support table, which it is found enable the bars to be more easily moved without "sticking fast" at their forward end edges, as will readily be appreciated. This is found to be a feature of our device of 55 moment from a practical standpoint in connection with the present type of bar pusher. The pusher head 7, consists of a casting preferably having an upstanding flange or stiffening rim 36, 37, 38, and a horizontal plate portion 39, which may be cut away at

40 to lighten the weight of the pusher head. There are also depending flanges 41, 41 on the sides of the head 7 which form guides for the head when operating along the ways 27, 27. On the flanges 41, 41 are the outstanding flanges 42, 43 having preferably pins 44 which pass through the chains 12, 13, thus positively connecting the movement of the pusher head with the movement of said chains. The forward end of the head 7 has teeth 18, 18 etc. formed complementary to the grooves 35 of the bar support table 33, and same are also it will be understood formed complementary to the grooves of the furnace hearth 20; so that when the grooves of the bar table and hearth are in alignment, a series of crossed bars as 31 and 32 Figure 5 can be simultaneously moved forward into the furnace 24. The teeth 18, 18 of the pusher head 7 are suitably stiffened by ribs 45, at intervals across the width of the head, as clearly shown in Figures 6 and 7 of the drawing.

The numerals 46, 46 indicate chain and sprocket guards which are preferably supported on the upturned transverse bar 47, carried by the ways 27, 27. The ends 48, 48 of said guards 46 are conveniently attached to the binding staves or channels 49, 49, of the furnace 24 as shown.

The operation of the present pusher is as follows. The motor 6 is operated in a reverse direction until the head 7 is in the retracted or dotted position 50, similar to the position in Figure 5 also, when the bars 31 are placed in the grooves 35 of the pusher by hand, the first transverse row illustrated by 31, and nearest the head teeth 18, all being placed with their angle of slope in the same direction. Next a second row as illustrated by bars 32, are placed in crossed relation, as shown in Figures 3 and 5, adjacent to the first row of bars. The motor is now operated in its normal or forward revolution, and the chains 12, 13 receiving motion from the same through the worm gearing 8, and shaft 9 are operated, carrying forward the head 7 and in this way all the bars are simultaneously advanced into the furnace 24, as is at once understood. The motor is now reversed, and the head 7 returned to its retracted position at 50, ready for more bars to be placed on the bar support table 33, preparatory to a second charging operation. In some cases it is found advantageous to have one or both of the sprockets 14 and 15 loose or idle on the shaft 30, so that the edges 41 do not jam against the edges 51, 51 of the bar table 33. In other words it tends to smoother operation of the pusher head 7.

From the above description it is evident that the particular specific form of pusher herewith presented is one which exactly meets the need for which it is designed, and

has proven its worth in actual mill use, being of simple construction, with few parts, positive in operation, easily operated, and altogether a very desirable sheet and tin mill 5 accessory.

I claim:

1. In a pusher, a pair of inclined ways mounted on a supporting means, a bar support table between the inclined ways, a series of V-shaped grooves formed in the bar support table, cut-away portions at the bases of said grooves, a slideable pusher head on the inclined ways, a series of V-shaped teeth on the pusher head adapted to operate in the bar table grooves, and power means for operating the pusher head teeth along the said grooves. 10
2. A pusher provided with a pair of drive sprockets and a pair of inclined ways mounted on supports, a grooved bar support table having cut-away portions at the bases of the grooves, mounted between the inclined ways, a pusher head slideably carried on the inclined ways, and having teeth formed complementary to the said bar table grooves, an outstanding flange on each side of the pusher head, power transmission means connecting the said drive sprockets with the pusher head flanges just mentioned, for the purpose of operating the pusher head along the aforesaid inclined ways. 20
3. A pusher having a base plate adapted to support a motor and a worm-gearing, a pair of inclined ways and a power shaft mounted on said base plate, a drive sprocket on each end of the power shaft, a pair of idler sprockets on the inclined ways, a grooved bar support table on the latter, a pusher head having teeth adapted to slideably operate in the bar table grooves, a pair of drive chains each passing over a drive and an idler sprocket, and secured to the pusher head, for the purpose of propelling the latter along the inclined ways. 30
4. In a pusher, a base plate adapted to support a motor and a worm-gearing, a pair of inclined ways and a power shaft mounted on said base plate, a drive sprocket on each end of the power shaft, a pair of idler sprockets on the inclined ways, a grooved bar support table on the latter, a pusher head having teeth adapted to slideably operate in the bar table grooves, a pair of drive chains each passing over a drive and an idler sprocket, and secured to the pusher head, for the purpose of propelling the latter along the inclined ways. 40
5. In a pusher, a pair of upright supports, a pair of recessed adjustable standards adapted to receive the outer lip of a furnace fore-plate, a pair of inclined ways each having one end thereof carried on one of the upright supports, and its opposite end carried on one of the recessed adjustable standards, a bar table mounted between the inclined ways, and a pusher head slideably mounted on the inclined ways and having teeth adapted to operate in the bar table grooves, and means for actuating the pusher head. 45
6. In a pusher, a pair of upright supports, a pair of recessed adjustable standards adapted to receive the outer lip of a furnace fore-plate, a pair of inclined ways each having one end thereof carried on one of the upright supports, and its opposite end carried on one of the recessed adjustable standards, a bar table mounted between the inclined ways, and a pusher head slideably mounted on the inclined ways and having teeth adapted to operate in the bar table grooves, and means for actuating the pusher head. 50
7. In a pusher, a pair of inclined ways mounted on supports, a bar table positioned between the inclined ways, and having the same angle of inclination as the latter, and a pusher head on the inclined ways adapted to reciprocate along the bar table and move a charge of bars therewith. 55
8. In a pusher, a pair of inclined ways mounted on supports, a bar table positioned between the inclined ways, and having the same angle of inclination as the latter, and a pusher head on the inclined ways adapted to reciprocate along the bar table and move a charge of bars therewith. 60
9. In a pusher, a unitary structure having a pair of inclined ways, a grooved bar table positioned between the latter, a pusher head adapted to reciprocate on the inclined ways, and engage the grooves of the bar table. 65

In testimony whereof I affix my signature.
HANNORA E. ALLIS,
*Administratrix of the Estate of Thomas V.
Allis, Deceased.*
